(57) **CLAIM**

The ornamental design for a microwavable container, as shown and described.

DESCRIPTION

The present invention is a new and ornamental design for a microwavable container to use in microwave oven.

FIG. 1 is a perspective view of a microwavable container, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a demonstration of which the top piece of the microwavable container is open.
